UNITED STATES PATENT OFFICE

ALBERT PORTEVIN, OF PARIS, FRANCE, ASSIGNOR TO SOCIÉTÉ D'EXPANSION TECHNIQUE, OF PARIS, FRANCE, A COMPANY OF FRANCE

APPARATUS FOR THE MANUFACTURE OF HOLLOW BODIES

Application filed November 7, 1927, Serial No. 231,729, and in France November 10, 1926.

A process for the manufacture of tubular bodies made from molten metal or other solidifiable fluid is already known, in which the fluid is deposited on the inner wall of a cylindrical mould to which is imparted a rotary movement about its axis and a movement of translation along the latter, or reversely, and in which process the fluid freely falls from the ladle into the projection lip or spout arranged in the mould.

The present invention has mainly for object an apparatus for the manufacture of steel pipes utilizing this process; the said invention particularly consists in replacing the single projection lip or spout producing a single jet of molten metal by a series of jets, the number of which is variable, and which constitute a real projection sheet.

The invention includes all the forms of construction of this device and particularly those which consist:

(a) In replacing the single projection lip or spout by a refractory deflector provided with several channels for side projection, substantially devised, as to their shape, in a similar manner to the vanes of a reaction turbine.

(b) In constructing this refractory deflector in which a way that it is entirely integral with the fixed hollow axis wherein enters the freely falling molten metal.

(c) Or again, in constructing a refractory deflector of this type, but in such a manner that the said deflector rotates in the same direction as the mould and at a speed which, although it is preferably equal to that of the rotation of the mould, can be different and adjustable at will.

(d) In particular, in forming this deflector in two pieces movable relatively to each other, the movable member forming the jets constituting the projection sheet; this member is caused to rotate either by the simple reaction of flow of the molten metal, or by a suitable driving device.

(e) In constituting the deflector in the shape of a crucible movable in translation relatively to the mould, but rotating with the latter, in such a way that the metal is forced along the walls of the said crucible

by centrifugal force, for reaching the walls of the rotating mould on which it adheres when solidifying.

The accompanying drawing illustrates, by way of example only, various forms of construction of the said improvements.

Fig. 1 is a sectional elevation of a first form of construction.

Fig. 2 is a sectional elevation of a second form of construction.

Fig. 3 is a sectional elevation of a third form of construction.

Fig. 4 is a sectional plan view of the third form of construction, showing the arrangement of the projection nozzles.

Fig. 5 is an elevation of a fourth form of construction.

In the example shown in Fig. 1, a refractory deflector *l*, in one piece, is hung on the tube *k*.

The said deflector is provided at 2 with a funnel-shaped recess into which enters the stream 3 of molten metal, freely falling. The lower portion of the recess 2 leads to substantially radial nozzles 4 which have preferably a horizontal section similar to that of the vanes of a reaction turbine.

It will be seen that the vein of molten metal is subdivided by the part *l'*, acting as a deflector, in several streams which issue from each of channels 4 instead of being directly projected on the mould by a single nozzle. The considerable difference of this arrangement relatively to that already known, consists in that the horizontal projection of the metal on the rotating mould is effected so to speak according to a circular sheet, instead of under the form of a single jet. The number of points of impact of the metal against the mould is therefore multiplied in the desired proportion, according to the number of channels 4 provided in the deflector *l*.

In the example of Fig. 2, the deflector *l* is hung to the tube *k* through the medium of a device such as a ball bearing for instance, permitting the free rotation of this deflector relatively to the tube *k*. In this example, the deflector *l* plays the part of a reaction turbine, that is to say the flow of

the molten metal through the channels 4 similar to vanes, ensures the rotation of this deflector. It is advantageous that the vanes or channels 4 should be arranged and devised in such a way that the rotation of this deflector takes place in the same direction as the rotation of the cylindrical mould.

In the example of Fig. 3, the deflector is also arranged in such a manner that it can 10 rotate relatively to the tube k . But the rotation of this deflector is controlled by a special motor 5 acting on a shaft 6 on which the deflector is rigidly secured. It is obvious that the motor 5 is different from the movable motor which ensures the rotation of the 15 cylindrical mould.

In the example of Fig. 5, the rotating mould is illustrated at 11; this mould is caused to rotate by the motor 12.

Within the mould 11 is arranged the deflector 13 which is provided with a central cavity 14 and is so arranged as to rotate with the mould 11, for instance under the simple action of the friction between the deflector 13 and the mould 11. The deflector 13 is movable in axial translation by any mechanical means and, for instance, by a double acting cylinder 15.

The vein 16 of molten metal falls to the 20 bottom of the cavity 14 of the deflector 13. The molten metal is caused to rotate by the said deflector 13 and the centrifugal force pushes the metal on the lips of this deflector until it reaches the wall of the mould 11, 25 under the shape of a sheet. The metal then settles on the walls of the mould 11, where it solidifies.

In this way, the projection of the metal against the walls of the cylindrical rotating 40 mould takes place in the form of a sheet, instead of a jet or of a series of jets. Moreover, it comes against the wall of the mould with the same angular speed as the latter, which is very favourable for obtaining the 45 result sought for. Finally, the rotating mould can be fixed in translation, the deflector being on the contrary movable in translation, while, in the known processes, the rotating mould is usually movable in 50 axial translation.

It is to be understood that there would be no departing from the scope of the present invention by maintaining the deflector fixed in translation, and by axially displacing the rotating mould.

The forms of construction described are obviously capable of receiving numerous modifications, particularly concerning the shape given to the deflector, the means for 60 producing its displacement or that of the mould, and even the shape of this mould; in fact, it is possible by this process to obtain tubes of any cross section: circular, elliptical, oval, or even polygonal, according 65 to circumstances.

It is obvious that such modifications remain within the scope of the invention.

What I claim as my invention and desire to secure by Letters Patent is:

1. In an apparatus for the manufacture 70 of tubular bodies, a deflector positioned to intercept an exposed descending stream of solidifiable fluid, said deflector being cupped and open at its upper end to receive the fluid and having a formation adapted to peripherally deliver said fluid, and a vertical tubular mould surrounding and co-axial with said deflector, said mould and deflector being adapted for relative movement in the direction of their axis and at least one 80 thereof being rotatable.

2. In an apparatus for the manufacture 85 of tubular bodies, a deflector positioned to intercept an exposed descending stream of solidifiable fluid, said deflector being cupped and open at its upper end to receive the fluid and being otherwise closed and being internally flared to peripherally deliver the fluid, and a vertical tubular mould surrounding and co-axial with said deflector, said mould 90 and deflector being adapted for relative movement in the direction of their axis and at least one thereof being rotatable.

3. In an apparatus for the manufacture 95 of tubular bodies, a vertical tubular mould along whose axis an exposed stream of solidifiable fluid descends, means for rotating said mould upon said axis, a plunger extending into said mould through the lower end thereof, and a head on the upper end of said plunger contacting with the mould wall, said head being cupped and open at its upper end to receive the exposed descending fluid, being otherwise closed, and being internally flared to peripherally deliver said fluid 100 against the mould wall.

In testimony whereof I have signed my name to this specification.

ALBERT PORTEVIN.
